US00D350446S

United States Patent [19]

Sauvage

[11] Patent Number: Des. 350,446

[45] Date of Patent:  Sep. 13, 1994

[54] TABLE SUPPORT STAND

- [75] Inventor: Thomas Sauvage, Huntersville, N.C.
 [73] Assignee: Rubbermaid Incorporated, Wooster, Ohio
 [] Term: 14 Years
 [21] Appl. No.: 49,622
 [22] Filed: Apr. 19, 1993

Related U.S. Application Data
